UNITED STATES PATENT OFFICE.

HENRI FRANCART, OF TONGRES, BELGIUM.

TUNNEL, FURNACE, KILN, OVEN, AND THE LIKE.

Application filed June 24, 1920. Serial No. 391,511.

(GRANTED UNDER THE PROVISIONS OF THE ACT OF MARCH 3, 1921, 41 STAT. L., 1313.)

To all whom it may concern:

Be it known that I, HENRI FRANCART, citizen of Belgium, residing at Tongres, Belgium, has invented certain new and useful 5 Improvements in or Relating to Tunnels, Furnaces, Kilns, Ovens, and the like, of which the following is a specification.

The present invention relates to the flame tunnel ovens wherein the articles under 10 treatment are advanced between stationary walls and it has for one of its objects an improvement in an apparatus of this type whereby the output and the efficiency of the apparatus is increased.

15 It is also an object of this device to provide a tunnel oven in which the products of combustion and the flames therefrom come in direct contact with the article to be heated and also one in which radiation covers an 20 important part.

This radiation produces effects which are all the more useful in that it helps to equalize and control the degree of heat at any point within the oven. This radiation is increased by the particular construction of the 25 interior of the oven walls which are so arranged that the radiation will be localized and will act upon the articles opposite cavities formed by certain flange structure.

30 Another feature of this device, is the peculiar construction of the flanges located within the oven whereby the displacement of the products of combustion through the tunnel is aided; other objects and advantages of 35 this device will be apparent from the following description taken in connection with the drawing which shows one embodiment of my invention.

I do not wish however to be limited by 40 the particular structure here shown.

In the drawings;

Fig. 1, is a vertical cross-section of the preferred embodiment of my invention.

Fig. 2, is a longitudinal horizontal section.

45 Fig. 3, is a view showing a longitudinal section with the flanges inclined for the purpose of aiding in the displacement of the products of combustion.

50 Fig. 4, is a modified form in cross-section of an oven adapted to be used for annealing purposes.

In the drawings, the numeral 1, represents a conduit by which the gas is supplied to the

oven. This conduit as shown in Figure 1 leads into each side of the oven. The gas 55 from the conduit 1 enters within the oven proper through cavities 2 at the bottom of the oven on each side thereof. These cavities 2 lead into the oven between flanges 3, which extend all the way across the upper 60 part of the oven and serve to localize the heat produced by the combustion of the gas and which also serve to produce radiating surfaces. The lower part of the flanges just above point of entrance of the gas into the 65 oven proper is hollowed out to form conduits 5 for placing the cavities formed by the flanges in communication with each other.

Within suitable space through the oven 70 there is provided a trackway on which trucks 4 containing the articles to be treated are placed.

The air which supports combustion enters the furnace from the end opposite to that 75 at which the objects to be treated enters. Any suitable means for producing a current may be used.

In the normal working order of the oven the normal products of combustion escape 80 toward the entrance of the oven while the air necessary for combustion enters at the exit of the oven and passes over the articles as they near the exit thereby cooling them off. The whole gaseous product of combustion in its longitudinal movement in the oven is retarded and given a circular motion by the flanges which act as radiating surfaces and as means for localizing the heat.

In order to assist in the longitudinal 90 movement of the gases flanges 3 are as shown in Figure 3 inclined from bottom upward, in the direction of the entrance of the oven so that the combustion which takes place at 2 in the cavity formed by flanges 3 95 suck up the gaseous mass from the oven toward the top by a system of longitudinal movement.

After the gas has entered through cavities 2 where combustion takes place and hot 100 gases are produced, the hot gases pass up the sides of the oven between the flanges 3 and are more or less concentrated in the upper part of the oven and therefrom force down upon and around the content to be 105 dried. The flanges 3 serve to localize and

equalize the heat and direct it down upon the contents. The process of drying is effected by the hot gas coming in direct contact with the articles.

- 5 In the form shown in Fig. 4 the general construction of the flanges is the same as that shown in the other figures but the flanges are prolonged below the level of the bottom of the oven. The hot burning gases 10 coming in enter the oven through openings 6, pass up through the flanges over and around the articles treated and back down through conduit 7. This form of oven is especially used for annealing purposes.
- 15 The outside surfaces of the kiln wall are indicated in Figs. 1, 3 and 4, by the light lines. The outside body of the wall may be built up of any suitable material that has a non-heat conducting quality.
- 20 Having now particularly described my invention, the nature of its structure and manner of its operation, what I claim is:
1. In a tunnel oven, an oven body, a series of flanges arranged within and extending 25 across the top of the body; gas conduits leading into the oven and between the flanges.
2. In a tunnel oven, a tunnel body, a series of flanges arranged within and ex-

tending across the top of the tunnel body, 30 gas conduits leading into the tunnel.

3. In a tunnel oven, a passageway therethrough for objects to be treated, a series of flanges extending over and across the passageway and providing combustion chambers and localizing means for the products of combustion, a gas conduit leading into the combustion chamber.

4. In a tunnel oven, a passage-way therethrough for objects to be treated, a series of 40 flanges extending over and across said passage-way and providing combustion chambers and localizing means for the products of combustion, a gas conduit leading into the combustion chamber, the lower part of each 45 flange being hollowed out to form conduits whereby the gas may pass from one cavity to the other.

5. In a tunnel oven having a passage-way therethrough, a series of flanges extending over and across the passage-way and providing combustion chambers, the lower part of said flanges being hollowed out to permit the products of combustion to pass from one 50 chamber to another.

In testimony whereof I affix my signature.

HENRI FRANCART.
